UNITED STATES PATENT OFFICE.

JAMES TAYLOR PLUMER, OF PONTIAC, MICHIGAN.

SPRAYER.

1,299,380.

Specification of Letters Patent.

Patented Apr. 1, 1919.

Application filed September 25, 1917. Serial No. 193,110.

To all whom it may concern:

Be it known that I, JAMES T. PLUMER, a citizen of the United States, and a resident of Pontiac, in the county of Oakland and 5 State of Michigan, have invented a new and Improved Sprayer; of which the following is a full, clear, and exact description.

My invention relates more particularly to apparatus adapted to spray a comparatively 10 large area through the medium of sprayer arms.

An object of the invention is to provide a spraying apparatus of the character indicated improved with respect to the frame 15 which is adapted to be adjusted to suit various widths of rows of plants, and having spraying means including a stand pipe so supported in the frame as to be revoluble and to be adjustable with the adjustment 20 of the frame to maintain the stand pipe approximately perpendicular.

An important object of the invention also is to provide an improved jet of very simple 25 form to control with facility the discharge of the water from the outlet orifices in the spraying arms or to entirely cut off the flow.

Other objects of the invention and the advantages of my improved construction will appear as the description proceeds.

30 Reference is to be had to the accompanying drawings forming a part of this specification in which similar reference characters indicate corresponding parts in all the views, it being understood that the drawings are 35 merely illustrative of one example of the invention.

Figure 1 is an end elevation with parts broken away of a spraying apparatus embodying my invention;

40 Fig. 2 is a side elevation thereof with parts broken away and others in section;

Fig. 3 is a partial vertical section on an enlarged scale;

Fig. 4 is a fragmentary plan view on an 45 enlarged scale given to show adjustable means for anchoring the stand pipe to a side of the frame;

Fig. 5 is a plan view of the superstructure from which guys run to the distributing 50 arms;

Fig. 6 is a fragmentary plan view of the lower portion of the superstructure on the stand pipe showing the winding drums for the guys;

55 Fig. 7 is a cross section through the stand pipe on the line 7—7, Fig. 3;

Fig. 8 is an enlarged cross sectional view of one of the distributing arms and an adjustable jet therein;

Fig. 9 is a fragmentary longitudinal section of one of the distributing arms;

Fig. 10 is a detail in horizontal section on the line 10—10, Fig. 3.

In the illustrated embodiment of my invention side frames designated generally by 65 the numeral 10 are provided adapted to be disposed at varying angles to each other. Each frame is provided with a suitable shoe 70 11 to facilitate the hauling of the frame and the supported spraying means, by connecting the frame members with suitable hauling means (not shown) or draft animals. In the illustrated frame a suitable number of bars 12 extend upwardly from the shoes 11, and various brace members 13 are em- 75 ployed.

In order to pivotally connect the upper 80 ends of the frames 10 longitudinal shafts or rods 14 are employed which pass through any suitable members on the upper ends of the bars 12, there being shown for the purpose, (see Fig. 1) brackets 12^a on said bars 12 through which the rods 14 pass. The inner ends of the rods 14 pass through a saddle ring 15 to which the rods are swiveled at 85 diametrically opposite points on the ring, so that the said ring may have rocking vertical movement. Within the ring 15 is a saddle plate 16 which is pivotally held in the ring at diametrically opposite points as through 90 the medium of screws 17 or the like which are at right angles to the pivotal connection of the rods 14 with the ring 15, the saddle plate 16 thus having a gimbal connection with the frames 10 permitting the saddle 95 plate to have universal movement.

A stand pipe 19 receives a supply of water in the manner hereinafter described and said stand pipe extends freely through a central opening 18 in the saddle plate 16. 100 To the stand pipe is secured a distributing head 21, the base 20 of which is revoluble on the saddle plate 16, the said base 20 and the saddle plate jointly forming a ball race for ball bearings 22. The head 21 has radially disposed nipples 23 to which distributing arms 24 are secured preferably by a suitable flexible connection, there being shown short lengths of hose indicated at 25 which permit the arms 24 to have various angular 110 positions relatively to the nipples 23. The distributing arms 24 are equipped with jets

26 hereinafter more particularly referred to. To strengthen the flexible connection between the arms 24 and nipples 23 I may employ yokes 25^a, best seen in Figs. 1, 3 and 8, each of which presents side arms pivoted as at 21^a to a nipple 23 and the opposite end suitably secured to the inner end of the adjacent distributing arm 24. In the example shown (see Fig. 8) a flanged nipple 25^b is secured by rivets or bolts 24^a to the flange 24^b of the distributing arm, said nipple 25^b receiving the adjacent end of the hose section 25.

To supply water to the stand pipe 19 the lower end of said stand pipe is revoluble in a receiving head designated generally by the numeral 27, here shown as having nipples 28 to either of which a water supply pipe or hose 29 is connected, the opposite nipple usually being capped as at 28^a. On the receiving head 27 is a stuffing box 30 and above the said stuffing box a bearing collar 31 around the stand pipe is provided with suitable bearing elements such as rollers 32. A collar 38 may be provided on the stand pipe 19 to constitute a rest for the collar 31. The collar 31 and stuffing box 30 are suitably suspended from the saddle plate 16, there being shown for the purpose rods 33 fastened in any desired way to the said saddle plate and secured at their lower ends to the bearing collar 31. Other hanger rods 34 suspend the stuffing box 30 from the collar 31. The stuffing box may include a flange 35 secured to the flange 36 of the stuffing box as by bolts 34^a. If desired, a collar 37 (Fig. 3) may be formed on or secured to the lower end of the stand pipe 19 to prevent the possibility of the stand pipe rising under the pressure of the water.

To adjustably anchor the collar 31 with a side 10 of the frame I employ a brace arm 39 and brace arms 40 at the sides of the arm 39, said arms being pivoted at their inner ends to the collar 31 and adjustably connected at their outer ends with a short longitudinal anchor bar 41 on the adjacent frame 10. The brace arm 39 has a slot and pin connection with the bar 41, there being a slot 42 in said brace arm, and a pin or bolt 43 extends through said slot and into a block 44 disposed between the side members of the bar 41. Any suitable nut 43^a or the like serves to tighten the bolt 43 to hold the arm 39 and block 44 in a given adjustment. To slidably and pivotally connect the outer ends of the arms 40 with the bar 41 in the illustrated example, upper and lower plates 45 are slidable on the said bar and receive bolts 46, said bolts passing also through blocks 47 disposed in pairs between the side members of the said bar 41. Between the blocks 47 of a pair a toothed pinion 49 is disposed and meshes with a fixed rack 48 on a side of the bar 41, each pin-

ion being secured to a pin or shaft 50, the upper end of which is square to receive a wrench as indicated at the bottom of Fig. 4, whereby to turn the pinions 49 causing the plates 45 and the outer ends of the brace arms 40 to travel longitudinally of the bar 44 whereby to adjust the collar 31 for permitting the stand pipe 19 to maintain an approximately vertical position as when the side frames 10 are on a hillside or inclined ground, for example.

As seen best in Figs. 8 and 9 each jet 26 is tapped into a side of a distributing arm 24. Each jet is threaded externally to engage threads in a jet orifice of the distributing arm and is formed with a longitudinal groove 52 of gradually increasing depth toward the inner end. Preferably the jet is offset to provide a handle member 26^a at the outer end for turning it. By screwing the jet more or less into the distributing arm 24, the groove 52 will regulate the flow of water to the jet or the flow may be entirely cut off by turning the jet until its cylindrical threaded portion effects a closure of the jet orifice.

Supported on the upper end of the stand pipe 19 and its distributing head 23 is a superstructure designated generally by the number 53 and including a tubular central member 54 flanged at its lower end and bolted as at 55 to the top of the head 23 in line with the stand pipe 19 to constitute in effect a continuation of the distributing head 23, the upper end of the tube 54 being capped or otherwise closed so as to act in a measure as an air chamber to contribute to maintaining a regular supply of water to the supply arms 24. Guys 56 extend from the superstructure 53 to the distributing arms 24 at various points along the same. Said guys are connected with winding means to wind in or pay out the same to dispose the distributing arms at different angles for which purpose I have illustrated drums 57 on the superstructure 53 at the bottom, the shafts of the drums being squared to receive a crank handle 58 and the drums having ratchet wheels 59 engaged by pawls 60. From the drums 57 the guys extend to the top of the superstructure 53 and pass over sheaves 61 from which the guys extend to the arms 24 to which they are made fast in any suitable manner. I may employ additional guys 62 secured at their inner ends to outriggers 63 on the top of the superstructure 53 and secured at the outer ends to the outer ends of the distributing arms 24 to limit the downward movement of said arms. In Fig. 1 the character 26^b indicates an end jet on an arm 24, said end jet corresponding with the jets 26.

The jets 26 are all disposed on the respective arms 24 in a similar direction so that the reaction may tend to turn the spraying

apparatus as indicated by the curved arrow in Fig. 1.

To strengthen the stand pipe 19 I insert a core therein designated by the numeral 64 and presenting radially disposed webs bearing against the inner surface of the stand pipe and dividing the same into chambers. The said stiffening core projects above the stand pipe 19 through the distributing head 10 21 and into the tube 54.

The side frames 10 are equipped with suitable means to hold the same in adjusted position, there being indicated transverse latch bars 65 pivoted at one end as at 66 to a longitudinal bar 10^a on one frame 10, the opposite end of each latch bar being adapted to be secured by a pin 67 to the similar longitudinal bar 10^a of the other frame 10, there being provided a longitudinal series of holes 20 in the latch bar as indicated at 68, Fig. 1, either of which holes may receive the pin 67.

I wish to state in conclusion that although the illustrated example constitutes a practical embodiment of my invention, I do not 25 limit myself strictly to the mechanical details herein illustrated, since manifestly the same can be considerably varied without departure from the spirit of the invention as defined in the appended claims.

30 Having thus described my invention, I claim as new and desire to secure by Letters Patent:

1. A spraying apparatus including a frame composed of side sections, means to 35 adjust the angular positions of the said frame sections, a saddle at the top of the frame, means establishing a universal connection between the saddle and the frame, a stand pipe supported by the saddle and depending therefrom, means to connect the stand pipe at its lower end with a source of water supply, laterally extending distributing arms in communication at their inner ends with the said stand pipe above the saddle, a bearing collar surrounding the stand pipe below the saddle, and means to adjustably anchor the said bearing collar to one of the frame sections.

2. An apparatus of the class described including a support, a stand pipe on said support, a distributing head on the stand pipe, sprayer arms, flexible connections between the sprayer arms and the distributing head, and yokes connecting the distributing head

and sprayer arms, said yokes being pivoted 55 at one end.

3. An apparatus of the class described including a supporting frame, a saddle, means establishing universal connection between the saddle and the frame, a stand pipe, 60 sprayer arms above the saddle, means establishing communication between the sprayer arms and the stand pipe above the saddle, means supporting the stand pipe on the saddle, said stand pipe extending downwardly 65 through the saddle, means to supply the lower end of the stand pipe with water, a bearing collar surrounding the stand pipe below the saddle, braces pivotally connected with the bearing collar, and means establishing an adjustable connection between the said braces and a side of the frame.

4. An apparatus of the class described including a supporting frame, a saddle, means establishing universal connection between 75 the saddle and the frame, a stand pipe, sprayer arms above the saddle, means establishing communication between the sprayer arms and the stand pipe above the saddle, means supporting the stand pipe on 80 the saddle, said stand pipe extending downwardly through the saddle means to supply the lower end of the stand pipe with water, a bearing collar surrounding the stand pipe below the saddle, braces pivotally connected 85 with the bearing collar, and means establishing an adjustable connection between the said braces and a side of the frame, said braces including an intermediate brace having a slot and pin connection with the frame, 90 and side braces connected at their outer ends with the frame for longitudinal movement on the frame; together with means to shift the outer ends of the said side arms.

5. An apparatus of the class described including a support, a stand pipe therein, a distributing head on the stand pipe, sprayer arms extending outwardly from the distributing head, a superstructure on the distributing head, drums on the superstructure, 95 guys extending upwardly from the drums, and sheaves on the superstructure above the drums over which sheaves the guys extend, the said guys extending from the sheaves 100 outwardly and connected with the sprayer 105 arms at various points on the same.

JAMES TAYLOR PLUMER.
